US0D1065550S

(12) **United States Design Patent** (10) Patent No.: **US D1,065,550 S**
(45) Date of Patent: ** Mar. 4, 2025

(54) **DEVICE FOR ILLUMINATION AND IMAGING OF A TARGET**

(71) Applicant: **Stryker Corporation**, Kalamazoo, MI (US)

(72) Inventors: **Gavin Michael Murray**, Vancouver (CA); **Gregory Vincent Browne**, Vancouver (CA); **James Elliott Cameron**, Victoria (CA)

(73) Assignee: **Stryker Corporation**, Portage, MI (US)

(**) Term: **15 Years**

(21) Appl. No.: **29/927,682**

(22) Filed: **Feb. 5, 2024**

(57) **CLAIM**

The ornamental design for a device for illumination and imaging of a target as shown and described.

DESCRIPTION

FIG. 1 is a perspective view of a device for illumination and imaging of a target showing a first embodiment of our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view of a device for illumination and imaging of a target showing a second embodiment of our new design;

FIG. 9 is a front view thereof;

FIG. 10 is a rear view thereof;

FIG. 11 is a left-side view thereof;

FIG. 12 is a right-side view thereof;

FIG. 13 is a top view thereof; and,

FIG. 14 is a bottom view thereof.

The broken lines in the drawings represent portions of a device for illumination and imaging of a target that form no part of the claimed design.

1 Claim, 14 Drawing Sheets
